WATER-IMPACT FUSE

Harry J. Nichols, Dayton, Ohio

Application October 22, 1932, Serial No. 639,126

16 Claims. (Cl. 102—39)

(Granted under the act of March 3, 1883, as amended April 30, 1928; 370 O. G. 757)

My invention relates to improvements upon the type of fuse disclosed in my Letters Patent No. 1,446,764. The object of my present invention is to improve and simplify the construction and operation of such fuses, as well as to render the same more efficient and safe under all circumstances, and to render the same substantially less expensive in production.

Other objects of my invention will appear from the following specification and the foregoing objects and their resulting advantages will be made more apparent therein.

In the drawings illustrating my invention, Fig. 1 is a central, longitudinal sectional view of a fuse embodying my invention showing the parts in their normal position;

Fig. 2 is a view similar to Fig. 1, but showing the parts in the position in which they detonate or deflagrate the charge with which the fuse may be associated;

Fig. 3 is a central longitudinal sectional view of a further simplified and more inexpensive fuse embodying my invention and adapted for attachment to the nose of bombs and pyrotechnic devices, and illustrating the parts in their normal positions;

Fig. 4 is a view similar to Fig. 3, but showing the parts in the position in which they are adapted to detonate or deflagrate the charge in the bomb or pyrotechnic device with which such fuse is associated.

In the drawings, in which like parts are indicated by the same reference characters, the species of my invention illustrated in Figs. 1 and 2 is adapted for attachment to projectiles to be fired from guns, while the species shown in Figs. 3 and 4 is designed for attachment to bombs as well as pyrotechnic devices that may be dropped from aircraft into, or upon the surface of, the sea and for other purposes.

Referring to the species of my invention shown in Figs. 1 and 2, 5 represents the fuse stock which, in the instance shown, constitutes an integral part of the projectile nose plug, or if desired, the same may be a separate portion screwed into or otherwise secured to the projectile nose plug. The fuse stock 5 is bored axially to form a cylindrical chamber 6 in which a piston 7 is slidably mounted. The forward portion of the fuse stock 5 is provided with a bore 8 preferably of larger diameter than, and communicating with, the bore 6, which bore 8 is provided with internal screw threads adapted to receive a cylindrical externally threaded nose plug 9. The plug 9 has

an axial opening 10 extending therethrough provided with an enlarged outer mouth which is normally closed by a sealing disk 11 inserted into and against the shoulder of the mouth where the disk is firmly secured in place by a ring 12. 5 The ring 12 is provided with an outwardly flaring central opening whose smallest diameter preferably conforms to the diameter of opening 10 in plug 9. The plug 9 is provided in its front face with a groove 9a which forms a relatively 10 thin wall 9b surrounding the mouth of plug 9 that is spun or otherwise turned over ring 12 to hold the ring securely in place.

The head of piston 7 may be flat, but I preferably form upon the head thereof a central conical projection 26 surrounded by a peripheral wall 21 separated from projection 26 by an annular recess having a transversely curved bottom wall, as shown in Figs. 1 and 2. Upon the inner end of piston 7 is a rigid piston rod 24 whose projecting end is provided with an enlarged head 28 from which extends firing pin 25. Normally, the inner face of head 28 rests against the base of a cup 21 having formed through the center thereof an opening 22 normally occupied by firing pin 25. 20 In the instance shown, the outer diameter of cup 21 conforms to the internal diameter of the bore 6, and the edge of cup 21 rests against the outer face of primer retaining ring 16 which is peripherally rabbeted at its forward end to engage 20 shoulder 6a in the bore of fuse stock 5. Primer holding ring 15 having projection 15a upon its forward face surrounding a shouldered recess adapted to receive the primer charge or pellet, is inserted into stock 5 with a primer gasket 20 of 35 paper, fibre, thin copper or other suitable material, substantially cup-shaped in form adapted to be pressed between said projection 15a and the opening through ring 16, which gasket 20 holds 40 in place the primer pellet 18. Threaded or otherwise secured in the rear end of the bore in stock 5, is a plug 14 to hold rings 15 and 16 and disk 21 firmly in the positions shown in Figs. 1 and 2. The plug 14 is provided with a central, longitudinal opening 17 extending through ring 15 45 into communication with the primer pellet 18, so that when the pellet is detonated the flame will pass through opening 17 to the charge exposed at or suitably adjacent the mouth of the 50 opening 17.

The fuse stock 5 is provided with screw threads upon its inner end which are adapted to engage in corresponding threads in the projectile.

Plugs 9 and 14 are each provided with longi- 55

tudinal openings 14a, as shown in Figs. 1 and 2, adapted to receive the prongs of a spanner wrench for screwing them into place when the same are provided with screw threads for their securement.

5 The strength of the cup 21 is such that when the fuse stock 5 as shown and described is secured into the nose of a projectile and such projectile is fired from a gun, that the shock of firing will not overcome the resistance of the cup 10 to the head 28 of piston 7 and that cup 21 will, under such circumstances, hold the piston 7 in place with the head of piston 7 against the plug 9.

The sealing disk 11 may be formed of metal, moisture proof fibre or other desirable material 15 of such strength in its confined position that the same is not ruptured by the shock of firing the projectile nor during its flight through the air, and yet the disk 11 must be sufficiently frail to be ruptured upon impact of the nose of the projectile 20 with water. Upon such impact, water is forced through the inwardly converging opening in ring 12, disrupts the sealing disk 11, flows through opening 10 in plug 9 and against the head of piston 7. If the head of piston 7 were 25 flat, or otherwise conformed to the shape of the juxtaposed surface of plug 9 the area of the opening 10 would limit the initial area of the thrust of the impacted water upon the head of piston 7. However, the recess in the piston head 7 surround 30 ing the conical projection 26, whose apex is centrally disposed relative to opening 10, permits the water, which rushes at great velocity through opening 10, to be spread uniformly about the conical projection 26 and to be deflected by the 35 curved base of the recess in the piston head, which reversed impacted water strikes against the interior surface of plug 9. The area of the jet of water against the head of piston 7 being of greater area than opening 10 exerts substantially greater 40 force against the piston initially than it would if the face of piston 7 were not so shaped. The head 28 of piston rod 24 is thus driven through the cup 21 by dishing the center of the cup and enlarges the opening therethrough, as shown in 45 Fig. 2. The diameter of opening 22 in cup 21 whereby the lesser diameter of piston rod 24 is freed from engagement with the wall of opening 22 and the firing pin 25 is permitted to strike, with the full force of the water against the piston 50 head, the primer gasket 20 and indent the same as shown in Fig. 2 to detonate the primer pellet 18 whose products are violently projected through opening 17 to explode the charge adjacent the mouth of opening 17.

55 In the form of my invention disclosed in Figs. 3 and 4, the fuse stock 5a is formed conical with an integral cylindrical wall 5b on its base enclosing a cupped recess 5c which is adapted to receive the forward end of the body of a bomb, pyrotechnic device or the like. Where a pyrotechnic device is to be provided with my fuse, such body is preferably formed of wood or other material of sufficient buoyancy to float the entire device upon the water, in which case the fuse stock 5a 60 and its attached metallic parts are of such weight as to maintain the pyrotechnic device vertically in the water with its fuse stock end or nose downward; the body portion being of such length and provided near its upper end with the usual vertical, laterally extending fins to maintain the device vertical while falling through the air after being released from an aircraft.

70 Openings 5e are provided at intervals in the wall 5b for the insertion of screws or nails for the attachment of fuse stock 5a to the bomb body.

Extending axially through the front or nose portion of fuse stock 5a is a bore 6a whose outer portion is of increased diameter from its inner portion, forming a shoulder 6b at their junction.

75 Tube 30, whose exterior diameter is adapted to be pressed into smaller bore 6a of fuse stock 5a, is provided at its forward end with a flange 31 adapted to engage shoulder 6b. Freely slideable within the tube 30 is a piston 1a having on its head a central conical projection 26a surrounded by a wall 27a of a structure and function substantially the same as that described for piston 7 in connection with Figs. 1 and 2. The opposite end of piston 1a is similarly formed with a central conical projection 26b surrounded by an outer 15 wall 27b. The walls 27a, 27b form the skirt of the piston whose outer surface is adapted to slide freely within the bore of tube 30. The rear end of tube 30 is provided with an enlarged bore 32 provided with shoulder 33 intermediate the normal bore of tube 30 and bore 32. Against shoulder 33 is adapted to be firmly seated a washer 34 of fibre or metal.

A primer supporting member 35 whose outer diameter is adapted to be inserted in the bore 32 25 of tube 30 is provided with an axial opening 17a extending therethrough whose forward flaring mouth 17b terminates in a shouldered cavity adapted to receive a primer pellet 18a. This primer pellet cavity and mouth 17b are formed 30 in a central projection 36 of member 35. The primer pellet 18a is adapted to be held firmly in place in its cavity by a cupped primer gasket 20a, preferably of fibre, thin copper or other suitable material having flange 20b. The gasket 20a is 35 adapted to be pressed in place over projection 36 with its bottom wall contacting the primer pellet 18a. The thus constructed and assembled primer supporting member 35 is inserted with its projection 36 surrounded by gasket 20a through 40 the opening in washer 34 with the flange 26b of gasket 20a clamped between the adjacent face of washer 34 and shoulder 37 of member 35 with a spring 38 surrounding projection 26b and the body of gasket 20a and extending between the adjacent 45 faces of piston 1a and washer 34. In this position member 35 is secured by spinning or otherwise forming the rear end of tube 30 over the tapering end 39 of member 35. The rear end of member 35 is provided with a recess 40 adapted 50 to receive a primer tube extending thence into the body of the bomb or pyrotechnic device for communicating the products of the detonated primer pellet 18a to the explosive or pyrotechnic component respectively of the bomb or pyrotechnic device.

The tube 30 is closed by a sealing disk 11a 55 extending continuously over the flanged end 31 of tube 30 and is there firmly sealed by a plug 9c whose outer smooth surface is adapted to fit 60 snugly within the bore 6a of fuse stock 5a where plug 9c is permanently secured in firm contact against disk 11a by spinning or otherwise forming the metal of the thin front edge of bore 6a over tapering shoulder 9d on the adjacent edge 65 of plug 9c, as shown in Figs. 2 and 3. Extending axially through plug 9c is opening 10a having flaring mouth 10b.

When the bomb, pyrotechnic or other device provided with my invention constructed in accordance with Figs. 3 and 4 strikes the water, its end provided with the fuse stock 5a will first enter the water at high velocity, due to the substantial distance through which it has fallen after being launched from the aircraft. Im- 75

pacted water will enter mouth 10b, thence through opening 10a, where it will disrupt disk 11a. Thereupon such impacted water will act upon the head of piston 1a, as previously described in connection with piston 1, and will drive piston 1a inwardly, compressing spring 38 until conical projection 26b strikes with substantial force and indents the head of cup gasket 20a and thereby detonates the primer pellet 18a whose products are discharged through opening 17a to occasion the detonation or deflagration of the explosive or pyrotechnic content of the bomb or pyrotechnic device enclosed in body 5d.

In connection with Figs. 3 and 4, it will be noted that the cupped disk 21 of Figs. 1 and 2 and its function are absent from the structure shown in connection with the improvement of my invention illustrated in Figs. 3 and 4. This is for the reason that there is no substantial shock to the release of a bomb or pyrotechnic device that there is incident to the firing of a projectile from a gun. Consequently, in the form of my invention illustrated in Figs. 3 and 4 the spring 38 is under all circumstances able to hold the piston 1a from impacting and detonating the primer pellet 18a except when the bomb, pyrotechnic or other device associated therewith impacts water.

The herein described invention may be manufactured or used by or for the Government of the United States for governmental purposes without the payment of any royalty thereon.

What I claim is:

1. In a fuse for projectiles, bombs and pyrotechnic devices, the combination of a fuse stock, a primer supporting member rigidly carried by said stock, a piston slidably mounted in said stock forwardly of said member, a firing pin carried by said piston, a primer supported by said member, a plug secured in the nose of said stock forwardly of said piston and provided with an opening therethrough adapted to communicate with the head of said piston, and sealing means between said plug and said piston for sealing said opening, whereby, when the nose of said stock impacts with water, impacted water will enter said opening, disrupt said sealing means and act upon said piston to drive said firing pin into detonating contact with the primer.

2. In a fuse for projectiles, bombs and pyrotechnic devices, the combination of a fuse stock, a primer supporting member rigidly carried by said stock, a piston slidably mounted in said stock forwardly of said member, a firing pin operatively related to said piston, a primer supported by said member, deformable means normally holding said pin away from said primer, an opening associated with the head of said piston, and impact releasable means for sealing said opening whereby, when the nose of said stock impacts with water, impacted water will enter said opening, unseal said sealing means, deform said deformable means and move said piston to drive said firing pin into detonating contact with the primer.

3. In a fuse for projectiles, bombs and pyrotechnic devices, the combination of a fuse stock, a primer supporting member rigidly carried by said stock, a piston slidably mounted in said stock forwardly of said member, a firing pin connected to said piston, a primer supported by said member, deformable means normally holding said pin away from said primer, a plug secured in the nose of said stock forwardly of said piston and

provided with an opening therethrough to communicate with the head of said piston, and impact releasable means for sealing the mouth of said opening.

4. In a fuse for projectiles, bombs and pyrotechnic devices, the combination of a fuse stock provided with a longitudinal opening in its nose, a primer supporting member rigidly carried by said stock, a primer carried by said member, impact releasable means for closing said opening, and means normally rigidly carried by said stock intermediate said member and said opening adapted to detonate or deflagrate the primer when actuated by the force of impacted water entering said opening.

5. In a fuse for projectiles, bombs and pyrotechnic devices, the combination of a fuse stock provided with a longitudinal opening in its nose, a member adapted to support a primer rearwardly of said opening, a primer carried thereby, a piston slidably intermediate said member and said opening, a rearward projection from said piston, a firing pin on said projection, deformable means rigidly carried by said stock in contact with the end of said projection and adapted to be deformed thereby to move said pin to detonate or deflagrate the primer by the force of an impacted medium entering said opening and acting upon said piston.

6. In a fuse for projectiles, bombs and pyrotechnic devices, the combination of a fuse stock provided with a longitudinal opening in its nose, a member supporting a primer rearwardly of said opening, a primer carried thereby, a piston slidably intermediate said member and said opening and provided with a rearward projection, a firing pin on the free end of said projection, deformable means rigidly carried by said stock in contact with the end of said projection and having a hole therethrough of lesser diameter than said projection adapted to be occupied by said pin, said projection being adapted to be driven through said hole to move said pin to detonate the primer by the force of an impacted medium entering said opening and acting on said piston.

7. In a fuse for projectiles, bombs and pyrotechnic devices, the combination of a fuse stock having a longitudinal opening therethrough enlarged at opposite ends, means mounted in the rearward enlargement of said opening and supporting a primer, a primer in said means, a plug secured in said rearward enlargement adapted rigidly to hold said means therein, said plug and means being provided with openings adapted to register with each other and with the primer, a piston not normally slidable in the unenlarged portion of said opening, a firing pin connected to said piston to detonate or deflagrate the primer, deformable means for normally securing said piston from rearward movement, and a separate plug secured in the forward enlargement of said opening and adapted to secure said piston from forward movement and having a hole therethrough.

8. In a fuse for projectiles, bombs and pyrotechnic devices, the combination of a fuse stock having a longitudinal opening therethrough enlarged at opposite ends, means mounted in the rearward enlargement of said opening and adapted to support a primer, a primer in said means, a plug secured in the rearward enlargement adapted rigidly to hold said means therein, said plug and means being provided with openings adapted to register with each other and with the primer, a piston not normally slidable in the un-

- enlarged portion of said opening, a firing pin carried by said piston to detonate the primer, deformable means for normally securing said piston from rearward movement, a separate plug secured in the forward enlargement of said opening to secure said piston from forward movement and having a hole therethrough, and impact releasable means for closing said hole through said separate plug. 5
- 10 9. In a fuse for projectiles, bombs and pyrotechnic devices, the combination of a fuse stock having a longitudinal opening therethrough, means rigidly mounted in said stock and adapted to carry a primer in said opening, deformable means rigidly mounted in said opening in advance of said primer means and provided with a hole therethrough, and a piston not normally adapted to slide in said opening in advance of said deformable means and provided with a projection having an enlarged head and a firing pin projecting from said head, said pin being normally in said hole and said head being larger than said hole and impinging against said deformable means. 15
- 15 10. In a fuse for projectiles, bombs and pyrotechnic devices, the combination of a fuse stock having a longitudinal opening therethrough, means rigidly mounted in said stock and adapted to carry a primer in said opening, a primer in said 20 means, deformable means rigidly mounted in said opening in advance of said primer and provided with a hole therethrough, a piston not normally adapted to slide in said opening in advance of said deformable means, a projection from said piston having an enlarged head, a firing pin projecting from said head, said pin being normally in said hole and said head being larger than said hole and in contact with said deformable means, a plug secured in the front of the fuse stock opening normally contacting the head 25 of the piston and provided with an opening therethrough, and impact releasable means for closing said opening in said plug. 30
- 30 11. As an article of manufacture for a fuse for projectiles, bombs and pyrotechnic devices, a piston having a projection extending from one end, an enlarged head on said projection, a pin extending from said head, a recess in the remaining end of said piston, and a conical projection in said recess. 35
- 35 12. In a fuse for bombs and pyrotechnic devices, the combination of a fuse stock having an opening therethrough having a shoulder near its rear end, a tube in said opening and having a 40 shoulder on its forward end cooperating with 45 said first shoulder, a piston slidable in said tube and having a firing pin projecting therefrom, primer supporting means secured in said tube rearwardly of said piston, a spring in said tube intermediate said piston and means, impact releasable means for closing said opening, and a plug secured in said opening and impinging said releasable means against said tube and provided with an opening therethrough. 50
- 5 13. In a fuse for projectiles, bombs and pyrotechnic devices, the combination of a fuse stock, a primer, a primer mounting member immovably carried by said stock, a firing member provided with a head and a firing point slidably mounted in said stock, a deformable cup member interposed between said firing member and said primer mounting member constituting the sole safety device of the fuse, and an opening positioned forwardly of and in communication with the head of said firing member, whereby, when said stock impacts with a soft target, the substance of the target will enter said opening and drive said firing member into exploding contact with said primer. 10
- 15 14. In a fuse for projectiles, bombs, and pyrotechnic devices, the combination of a fuse stock, a primer mounting member immovably carried by said stock, a primer firing member provided with a head and a firing point slidably mounted in said stock, and a deformable cup member interposed between said firing member and said primer mounting member, said deformable cup member constituting the safety device of said fuse. 20
- 25 15. In a fuse for projectiles, bombs and pyrotechnic devices, the combination of a fuse stock, a primer, a primer mounting member immovably carried by said stock, a primer firing member provided with a head, a stem, and a firing point, and a deformable cup member provided with a central hole through which projects part of the 30 firing member, said cup member being adapted to prevent contact of said firing point with said primer until impact with the target occurs. 35
- 40 16. In a fuse for projectiles, bombs, and pyrotechnic devices, in combination, a fuse stock, a primer, a primer mounting member immovably mounted in said stock, primer firing means including a head, a firing point and an intermediate member, and a deformable cup member provided with a central hole adapted normally to 45 pass the firing point but not the intermediate member of said firing means, said cup member comprising the safety device of the fuse. 50

HARRY J. NICHOLS. 55
